ARTHUR L. PICKERING, OF ANDERSON, INDIANA.

GAS-REGULATOR.

1,015,975.

Specification of Letters Patent.

Patented Jan. 30, 1912.

Application filed November 9, 1910. Serial No. 591,429.

REISSUED

To all whom it may concern:

Be it known that I, ARTHUR L. PICKERING, of Anderson, county of Madison, and State of Indiana, have invented a certain 5 useful Gas-Regulator; and I do hereby declare that the following is a full, clear, and exact description thereof, reference being had to the accompanying drawings.

The object of this invention is to provide 10 an improved construction of combined gas seal and regulator in which there is a movable diaphragm, a mercury seal and a lever used for operating the valve which controls the gas inlet.

15 The features of the invention will be understood from the accompanying drawings and the following description and claims.

In the drawings Figure 1 is a central vertical section through the regulator. Fig. 20 2 is a vertical section on the line 2—2 of Fig. 1. Fig. 3 is a horizontal section on the line 3—3 of Fig. 1. Fig. 4 is a vertical section on the line 4—4 of Fig. 1.

There is shown herein a casing consisting 25 of a main portion 10, with the upper side partially open, and a top 11 secured together by bolts 12. At one side portion of the casing there is a gas inlet 13 and above it a gas outlet 14. Between the main part 30 of the casing 10 and the top 11 a flexible diaphragm 15 is secured along its edges, and upon said diaphragm a stiff plate 16 is centrally secured, and beneath the diaphragm there is a mercury seal consisting 35 of a cup 17 for the mercury 118, said cup being secured centrally to the diaphragm 15 and plate 16 by a hollow screw 18 which extends through said diaphragm and plate and carries on its upper end a flaring or 40 funnel shaped basin 19 which surrounds a tube 20, which screws into the bottom of the basin and centrally of the screw 18 and in communication with the opening through said screw. The tube 20 extends through 45 a hollow screw 21 which surrounds it at its upper end and discharges into a tube 22, which is the outlet for excess gas in order to relieve the surplus gas pressure and maintain it uniform. The tube 22 has a collar 50 23 screwed on it which is held down by the thimble 24, which screws on to the extension 25 from the top 11. The extension 25 is internally threaded for the hollow screw 21. A spring 26 surrounds the tube 20 and 55 rides between the screw 21 and the basin 19 and tends to hold the diaphragm in its

downward position. Holes 27 through the lower part of the tube 20 lead into the lower part of the basin 19. The mercury cup has an inlet opening 30 at one side, see Fig. 4, 60 which is in communication with the chamber below the diaphragm and through which the gas enters the mercury cup. Within the cup there is a partition 31 extending from the top of the cup at one 65 side of the outlet 32 down to a cylindrical portion 33, which extends below the middle of the cup. The portions 33 and 33 serve as a partition in association with the mercury which extends above the bottom of the 70 cylinder so as to form an inlet chamber in said cup on one side, and the gas is restrained from passing from one chamber to the other unless its pressure is great enough to force its way through the mercury and 75 under and around the partition or cylinder 33. When it does so, the gas will escape through outlet 32 and tubes 20 and 22.

A lever 40 is fulcrumed on the pin 41 extending transversely in the casing, see Fig. 80 3. The lever has two downwardly inclined arms 140 adapted to project beneath the pin 41, and a screw 240 screws through the lever, which rests on the pin 41 so as to project beyond the pin 41 somewhat and 85 form means for fulcruming the lever 40 on the pin 41 which cannot escape from said pin excepting when the screw is released. The actuated end of the lever 40 projects through a central opening 43 in the cylinder 90 33 of the mercury cup. An annular knife edge 44 surrounds the lever 40 to furnish satisfactory bearing. Hence, when the diaphragm moves up or down, said lever 40 will be correspondingly actuated. The 95 actuated end of the lever 40 projects through a frame 45, see Fig. 2, which has a screw 46 passing through the top thereof into the lever and has also an oval edge bearing 47 on the underside of said lever, 100 and a valve 48 is secured to the underside of said frame so as to normally rest upon the plate 49, through which the inlet port 50 extends. Hence when the diaphragm moves upwardly, the valve will close the 105 inlet port, and when the diaphragm moves downwardly, said valve will be correspondingly opened.

The outlet 14 is externally threaded for the union 60 which clamps on the nipple 110 61 with which an outlet tube may be connected.

- The location of the mercury seal or cup simplifies the construction of the regulator, as it forms a connection between the diaphragm and valve lever and forms part 5 of the weight with the coöperation of the coiled spring 26 to give a determined gas pressure. In relation to the foregoing it serves as a mercury seal. The mercury particles which may be carried up by the 10 surface plus gas will fall back over the upper end of the tube 20 and pass through the hollow screw 21 and be collected in the basin 19 and return through the holes 27 and gas outlet 32 to the mercury cup 17.
- 15 The valve for controlling the inlet of the gas is so constructed that it may be removed and cleaned or replaced with another without taking the regulator out of line. The lever 40 is so formed or cast that it may be 20 mounted on the fulcrum pin 41, and said fulcrum pin may be cast into the body of the casting and thus prevent the leakage of gas at the point where the fulcrum pin would otherwise be mounted in the casing.
- 25 There is an inward projection at the inlet 30 which prevents the escape of mercury through said gas inlet.

I claim as my invention:

- 30 1. A gas regulator including a casing, a diaphragm therein, a plate centrally secured upon the diaphragm, a mercury cup centrally secured to the underside of the diaphragm and provided with inlet and outlet openings adapted to be separated by 35 mercury so as to form a mercury seal, a fixed outlet passageway leading from the top of the casing, a tube leading from the outlet opening of the mercury cup and discharging into said fixed outlet passageway,

and a spring tending to force the diaphragm 40 down.

2. A gas regulator including a casing, a diaphragm therein, a plate centrally secured upon the diaphragm, a mercury cup centrally secured to the underside of the diaphragm and provided with inlet and outlet 45 openings adapted to be separated by mercury so as to form a mercury seal, a fixed outlet passageway leading from the top of the casing, a tube leading from the outlet opening of the mercury cup and discharging into said fixed outlet passageway, a spring surrounding said tube and having holes near the lower end thereof, a basin surrounding the lower part of said tube, and a spring surrounding said tube and bearing 50 down upon said basin so as to tend to press the diaphragm.

3. A gas regulator including a casing having an inlet port, a valve for controlling 60 said port, a diaphragm, a lever for controlling said valve said lever having a downwardly inclined projection, a fulcrum pin secured within the casing and projecting 65 between the main portion of said lever and the downwardly inclined projection, and a screw extending between the main portion of said lever in position to engage the fulcrum on the side opposite said projection 70 for holding the lever on said fulcrum pin.

In witness whereof, I have hereunto affixed my signature in the presence of the witnesses herein named.

ARTHUR L. PICKERING.
